(57) **CLAIM**

The ornamental design for a battery module assembly as shown and described.

DESCRIPTION

FIG. 1 is a bottom, front and right side perspective view of a battery module assembly showing our new design; FIG. 2 is a top, rear and left side perspective view thereof; FIG. 3 is a front elevational view thereof; FIG. 4 is a rear elevational view thereof; FIG. 5 is a left side view thereof; FIG. 6 is a right side view thereof; FIG. 7 is a top plan view thereof; FIG. 8 is a bottom plan view thereof; FIG. 9 is an enlarged view of portion 9 in FIG. 1; FIG. 10 is an enlarged view of portion 10 in FIG. 1; FIG. 11 is an enlarged view of portion 11 in FIG. 2; and, FIG. 12 is an enlarged view of portion 12 in FIG. 2.

1 Claim, 12 Drawing Sheets
